ARTICLE HANDLING AND SORTING APPARATUS

Dwin R. Craig, Falls Church, Va., Gregory J. Harmon, Bethesda, Md., Daniel E. Houghton, Arlington, Va., and Charles W. Hurley, Gaithersburg, Md., assignors to Reed Research, Inc., Washington, D.C., a corporation of Delaware

Filed Dec. 30, 1954, Ser. No. 478,694

1 Claim. (Cl. 209—91)

This invention relates to article handling and sorting apparatus. More specifically, it is concerned with apparatus for handling and sorting articles such as mail according to predetermined classifications. It particularly concerns the separation of large envelopes from standard size envelopes.

Field of the invention

Postal authorities are constantly under pressure from the public to process mail and to deliver it to the addressee in the minimum possible time. The handling of mail between the original posting and final delivery involves a complex series of operations and there are continual development programs sponsored by postal authorities, mail handling equipment firms, and other groups aimed at developing equipment or procedures which may eliminate or reduce the time required to carry out one or more of the operations required to process mail from the sender to the receiver.

Objects

A principal object of this invention is the provision of new apparatus for the handling and sorting of articles, particularly mail.

Further objects include:

(1) The provision of machines which make it possible to take completely unsorted mail and separate large envelopes therefrom, completely automatically and in a commercially feasible manner.

(2) The provision of new apparatus for automatically ejecting all envelopes which have a height above a predetermined minimum from a plurality of envelopes travelling at high speed in a vertical position along a substantially horizontal path.

Detailed description

A more complete understanding of the new apparatus of this invention may be had by reference to the accompanying drawings in which:

Fig. 1 is a schematic plan view of an article handling and sorting machine incorporating the oversize envelope separator of this invention.

Fig. 2 is a side elevational view of the oversize envelope separator and associated envelope knock-down or rearranging means.

Fig. 3 is an enlarged detailed sectional view taken along the line 3—3 of Fig. 1 showing the oversize envelope separator unit of the article handling machine.

Referring in detail to the drawings (see Fig. 1), an article handling and sorting apparatus is shown schematically to illustrate a typical utilization of the oversize envelope separator of this invention. Unsorted mail is deposited on conveyors which empty into package separator means 2, which removes packages and deposits envelope mail on high speed conveyor belts in a sub-

2

stantially vertical position. These conveyed envelopes then pass through oversize envelope separator means 4 and the envelopes which are of standard sizes leave separator means 4 on conveyor belts to be spaced, stamp-sensed, sorted, stacked, and cancelled.

A major step in mail handling is the separation of oversize envelopes or other flat mail from the partially sorted mail delivered by package separator 2 onto conveyor belt 162. This is accomplished in oversize separator 4 and is preferably preceded by a step of rearranging any envelopes which may be running along the belt 162 with their longest side in a vertical position rather than a horizontal position.

Referring to Figs. 2 and 3, belt 162 as it passes from beneath package separator 2 is provided with two vertically extending guide walls 166 which form between them the conveying channel 168 in which envelopes 84 travel being supported upon their bottom edge in a substantially vertical position.

An envelope knock-down device 170 is provided for rearranging envelopes, such as envelope 84a which may be travelling on belt 162 with the short edge, rather than the long edge, resting on the belt. The knock-down device 170 comprises a plurality of chains or heavy cords

172 which are fastened by their top ends upon the frame 174 so that they dangle into the channel 168. The lower ends of chains 172 are about 5 inches above the top of the belt 162 so that improperly positioned envelopes such as 84a come in contact with the chains and are knocked down into the desired position with the longest edge resting on the belt 162 while envelopes of the standard size travelling in the desired position do not come in contact with the chains 172. Of course, oversize envelopes or other large flat mail such as 84b will contact

chains 172 and may be flipped over from one side to another by the device 170, but this is of no consequence since this large flat mail is next removed by the oversize separator 4.

Referring further to Figs. 2 and 3, the oversize separator 4 comprises a plurality of driven rollers 176 and idler rollers 178 all of which are positioned so that the axes about which they rotate are oriented at an acute angle to the belt 162.

The driven rollers 176 are fixed upon a drive shaft 180 which is journalled in the arms 182 fixed upon the frame 184. The arms 182 also carry a motor 186 which, by means of the belt 188 and drive pulley 190, fixed to the shaft 180, rotates rollers 176 in the direction indicated by the arrow on Fig. 3.

The idler rollers 178 are rotatably carried upon arms 192 pivoted at their lower end upon the frame 184. Arms 192 are spring loaded so as to urge rollers 178 toward rollers 176.

A hopper device 194 is fastened above the rollers 176 and 178 to the channel walls 166. The hopper 194 catches oversize mail, such as envelope 84c, as it is thrown upwardly by the separator device 4 and drops it on conveying means (not shown) for delivery to other handling operations.

Having thus described an exemplary embodiment thereof, what we claim as our invention is:

In a mail sorting and handling machine, a large envelope separating device comprising a vertically extending channel open at both top and bottom, a belt beneath the bottom opening of said channel to support envelopes on edge confined within said channel and convey the envelopes along the channel, rollers supported on both sides of said channel upon axles which have their axes of rotation in a plane parallel to the plane of said channel and at an acute angle to said belt, the bottom edge of the rollers being a predetermined distance above said belt,

means to urge the rollers toward one another while permitting them to move away from one another when caused to do so by an envelope passing between them, and means to rotate at least one of the rollers, said rollers adapted to grip envelopes passing therebetween.
